UNITED STATES PATENT OFFICE.

JOHN W. GHEEN, OF ASTORIA, OREGON.

STEAM-ACTUATED VALVE.

SPECIFICATION forming part of Letters Patent No. 403,187, dated May 14, 1889.

Application filed February 2, 1889. Serial No. 298,459. (No model.)

To all whom it may concern:

Be it known that I, JOHN WESLEY GHEEN, of Astoria, in the county of Clatsop and State of Oregon, have invented a new and useful 5 Improvement in Steam-Actuated Valves, of which the following is a full, clear, and exact description.

This invention more particularly relates to the steam-cylinder part of a direct-acting 10 steam-pump and its valves and passages—that is, to the driving end of the pump—the other or water-cylinder end of the pump being of the ordinary or any suitable kind. In this connection said invention more particularly 15 relates to valve arrangements in such steam-pumps or driving-cylinder end thereof in which the valve controlling the motion of the main piston is a steam-actuated one, and is in its turn controlled by other valves, which 20 have their action governed by the main or driving piston.

The invention consists in a novel construction and arrangement of the valves and passages of the steam or driving cylinder of the 25 pump, and in certain cocks or attachments, substantially as hereinafter described, and pointed out in the claims, and whereby the 30 exhaust-steam is made to perform an important part in the slow movement of the main valve, and all jerking or irregular action is avoided.

Reference is to be had to the accompanying drawings, forming a part of this specification, in which similar letters of reference indicate 35 corresponding parts in both the views.

Figure 1 represents a side elevation of the steam-pump complete; and Fig. 2, a vertical longitudinal section of the driving or steam cylinder end of the pump, to which part my 40 invention relates.

A is the steam-cylinder of the pump, and B the water-cylinder thereof, which latter may be of the ordinary or any suitable construction, and the piston of which is operated in a 45 direct manner by the rod b, connecting said piston with the driving-piston C of the steam-cylinder, as in other direct-acting pumps.

D is the valve, which controls the movement of the piston C in the cylinder A. This 50 valve, which is a slide one, and is shown as of a double-D kind, being provided with two cavities or passages, c c, in its face, but it

may be otherwise suitably constructed, is arranged to work freely or independently within a steam-chest, E, from which the usual passages, d d, lead to opposite ends of the cylinder A to reverse the action of the piston C, and which passages, as well as the main or general exhaust-port e, are controlled by the valve D.

The steam-chest is constructed above to form a cylinder, g, having its length in the same direction as that in which the valve D slides or moves. This cylinder serves to receive in a close-working manner within it a 65 piston, F, attached to the valve D, for the purpose of operating the latter, said piston being provided with double heads h h, one near either end, and with reduced opposite terminal extensions, i i, which are arranged to work 70 as pistons in and out of reduced cylindrical chambers k k at opposite ends of the body of the cylinder g. Cocks l l are also provided at opposite ends of the valve-cylinder or terminal chambers i i thereof.

Steam is admitted to the valve-chest between the heads h h of the piston portion of the valve D by an inlet, m, as usual.

At opposite ends of the main cylinder A are two smaller cylinders or cylindrical chambers, G G—that is, one at either end of the main cylinder and in line with it. These cylinders G G are connected intermediately of their length by passages n n with the reduced terminal chambers or extensions k k 85 of the cylinder g, and these passages n n again in their turn are connected by branch passages o o with the enlarged portion of the cylinder g, near the opposite ends thereof, so that the heads h h of the piston portion of the valve 90 D may control them.

The small cylinders G G, too, are each provided with a live-steam port, r, near their outer end, and with an intermediate exhaust-port, s, which ports may respectively connect 95 with the steam or valve chest E and with the general exhaust-outlet e—that is, the steam-ports r with the valve-chest and the exhaust-ports s with the exhaust-outlet e—or the ports r may be otherwise supplied with live-steam 100 and the exhaust-port s have an independent or different outlet. Within said cylinders G G are fitted to work freely as pistons independent valves H, having each a reduced body

and opposite flange-heads, and each valve provided with a stem, *v*, that normally projects within the main cylinder *A*. These valves *H*, which are operated in their one or outer direction by the piston *C* coming in contact with their stems *v*, and are moved by the pressure of steam on their backs in an opposite direction, serve to control the passages *n n*, so as to pass steam admitted by the ports *r* to the outer ends of the cylindrical chambers *k k*, outside of the ends of the cylindrical valve-extensions *i i*, or to exhaust-steam by the ports *s s* from said chambers *k k*.

The operation is as follows: When the parts are in the position as represented in Fig. 2 of the drawings, the valve *D* is balanced—that is to say, is restrained from moving either way—by the passages *n n* at both ends establishing connection between the live-steam ports *r r* and the cylindrical chambers *k k* at opposite ends of the piston portion of said valve, and to throw the valve *D* pressure must be removed from one end of the piston portion of the valve. As represented in the drawings, the valve *D* has been thrown to the left and is passing steam by the left-hand passage *d* to move the piston *C* to the right, and as said piston approaches the end of its stroke in that direction it strikes the stem *v* of the right-hand supplementary valve *H* and moves the latter so as to shut off steam-supply entering by the right-hand port *r* from the right-hand passage *n* and opens said passage *n* to the exhaust *s* in the right-hand cylinder *G*. This takes off pressure from the right-hand end of the piston portion of the valve *D* while steam is being supplied by the left-hand passage *n* from the left-hand port *r* to the opposite or left-hand end of the piston portion of the valve *D*, to throw said valve to the right or move it in the same direction as the piston *C*, when approaching the end of its stroke, is moving. This shifting of the valve *D* reverses the action of the piston *C* when or in due course said piston strikes the stem *v* of the left-hand supplementary valve *H*, to move said valve and open the left-hand passage *n* to the exhaust-port *s* in the left-hand cylinder *G*, when the operation, as before described, is repeated to move the valve *D* back to its original position to the left, to again reverse the action of the piston *C*, the valve *D* always moving in the same direction as said piston. Either valve *H* resumes its normal inward position as the piston *C* leaves it by the live steam which enters by the port *r*, the cylinder of such valve acting upon the outer end of said valve. The piston portion of the valve *D* covers alternately by its heads *h h* the passages *o o* as said valve is moved, and whatever steam is caught by either piston-head *h* after its terminal extension *i* enters

the cylindrical chamber *k*, which it fits, will form a cushion on said piston-head to ease up the throw of the valve.

By the construction of the piston portion of the valve *D* with a reduced head-extension, *i*, at its opposite ends, and so that the enlarged piston-head parts *h* fit the cylinder *g* and the reduced extensions *i* the chamber *k*, only one at a time of the piston-heads *h* will be exposed on its outer face to the full pressure of the live steam after the valve *D* has been fully thrown, whereby said valve will be held closed in the position to which it was last moved, and so keep the ports to the main cylinder *A* wide open till the piston *C* strikes one of the small valves *H* and moves it to exhaust the steam from the end of the main-valve cylinder, in which the piston-head *h* of the valve was fully exposed to the live steam.

The cocks *l l* on the ends of the valve-cylinder *g* serve the purpose of starting or moving the valve *D* and of setting or keeping the whole mechanism in motion whenever necessary or when there is any failure to work automatically. This is done by opening either one of the cocks *l* and keeping the other of said cocks closed, when the steam issuing from the open cock will cause there to be a reduced pressure on the end of the piston portion of the valve *D* next to said open cock, while the full pressure will be maintained on the opposite end of the piston portion of said valve *D*, thus causing the latter to be moved.

The invention is not only applicable to direct-acting pumps, but also to direct-acting engines for other than pumping purposes.

Having thus described my invention, I claim as new and desire to secure by Letters Patent—

In reciprocating-piston engines for steam-pumps and other purposes in which the reciprocating action of the piston within its cylinder is controlled by a steam-thrown valve, which in its turn is controlled by valves actuated by the engine-piston, the combination, with the engine or main valve having opposite end piston-heads, *h h*, and opposite terminal reduced cylindrical extensions *i i*, of the valves *H H*, arranged to work within cylinders *G G* for direct action by the engine-piston, as described, said cylinders having steam and exhaust ports *r s*, and the valve-chest constructed with a cylindrical body portion, *g*, and cylindrical end chambers, *k k*, and having steam-passages *n n*, with branch passages *o o*, arranged to connect with the cylinders *G G*, substantially as and for the purposes herein set forth.

JOHN W. GHEEN.
